ATTORNEY.

UNITED STATES PATENT OFFICE.

CLYDE M SEMLER, OF AKRON, OHIO.

DESIGN FOR A FENDER LIGHT.

Application filed August 4, 1924. Serial No. 10,370. Term of patent 14 years.

To all whom it may concern:

Be it known that I, CLYDE M SEMLER, a citizen of the United States, residing at Akron, in the county of Summit and State of Ohio, have invented a new, original, and ornamental Design for Fender Lights, of which the following is a specification, reference being had to the accompanying drawings, forming a part thereof.

In the drawings:

Figure 1 is a front elevation of a fender

light embodying the design of the invention;

Figure 2 is a side elevation thereof.

Referring to the drawings, it will appear that the casing of the fender light has a torus of rubber thereon in simulation of a tire.

I claim:

The ornamental design for a fender light as shown and described.

CLYDE "M" SEMLER.
